US00D734740S

(12) **United States Design Patent**
Erbeus

(10) **Patent No.:** **US D734,740 S**
(45) **Date of Patent:** **** Jul. 21, 2015**

(54) **SPEAKER**

(71) Applicant: **Sony Mobile Communications AB**,
Lund (SE)

(72) Inventor: **Henrik Erbeus**, Göteborg (SE)

(73) Assignee: **Sony Mobile Communications AB**,
Lund (SE)

(**) Term: **14 Years**

(21) Appl. No.: **29/494,191**

(22) Filed: **Jun. 18, 2014**

(30) **Foreign Application Priority Data**

Mar. 12, 2014 (EM) 002423350-0001

(51) **LOC (10) Cl.** **14-01**

(52) **U.S. Cl.**

USPC **D14/214**

(58) **Field of Classification Search**

USPC D14/214, 215, 216, 221; 381/345

CPC H04R 1/02; H04R 1/023; H04R 1/025
